CLAIM

The ornamental design for a drinking product, as shown and described.

DESCRIPTION

FIG. 1 is an in use top perspective view of a drinking product showing my new design;

FIG. 2 is a front elevational view thereof;

FIG. 3 is a right side view thereof;

FIG. 4 is a rear elevational view thereof;

FIG. 5 is a bottom plan view thereof;

FIG. 6 is a top plan view thereof;

FIG. 7 is a rear elevational view of the drinking product showing my new design with the unclaimed base removed for ease of illustration;

FIG. 8 is a front elevational view thereof;

FIG. 9 is a top plan view thereof;

FIG. 10 is a top perspective view thereof;

FIG. 11 is a left side elevational view thereof; and,

FIG. 12 is a bottom plan view thereof.

The broken lines in the drawings are included for the purpose of illustration and form no part of the claimed design.
